UNITED STATES PATENT OFFICE.

HARRY B. BARNUM, OF STRATFORD, CONNECTICUT, ASSIGNOR TO THE AMERICAN FABRICS COMPANY, A CORPORATION OF CONNECTICUT.

DESIGN FOR LACE.

Application filed November 1, 1923. Serial No. 7,640. Term of patent 14 years.

To all whom it may concern:

Be it known that I, HARRY B. BARNUM, a citizen of the United States, residing at Stratford, county of Fairfield, State of Connecticut, have invented a new, original, and ornamental Design for Lace, of which the following is a specification, reference being had to the accompanying drawing, forming part thereof.

The figure is a fragmentary plan view of a piece of lace showing one of the medallions which forms the basic structure of the design, a piece of lace being made up of a succession of these medallions.

I claim:

The ornamental design for lace substantially as shown.

HARRY B. BARNUM.
